CONVERSION OF HYDROCARBONS

Joseph G. Alther, Chicago, Ill., assignor to
 Universal Oil Products Company, Chicago, Ill.,
 a corporation of South Dakota

Application May 26, 1928. Serial No. 280,704

3 Claims. (Cl. 196—59)

This invention relates more particularly to the treatment of hydrocarbons to produce therefrom, by conversion, high yields of desirable conversion products.

5 In the cracking of hydrocarbons where it is desired to obtain substantially high yields of gasoline-like products from the charging stock, the residuum produced in the process may contain objectionable amounts of solids comprising 10 carbon, coke, sludge, pitch or the like, which frequently make the residuum undesirable for use as fuel, recharging stock, or for other commercial purposes.

In a process of the type of the so-called recycling process wherein the oil is first passed 15 through a heating tube and then into an enlarged expansion, reaction and/or separating chamber from which the residuum is withdrawn, and from which the vapors evolved pass into a dephlegmator where they are subjected to fractionation, the condensed vapors being returned as reflux condensate to the inlet of the heating tube for retreatment, a method is successfully carried out whereby conversion of the oil can be accomplished with a relatively high yield of desirable 25 lighter gasoline-like products, together with the production of a residuum containing a very small amount of carbon, sludge or the like, while the production of carbon, coke, pitch, sludge and non-condensable gas (which are generally undesirable 30 products) is materially reduced.

This method comprises preventing the non-vaporized residual portions of the oil in the pressure reaction chamber from remaining in said 35 chamber under cracking temperature for any substantial length of time, thus preventing over-cracking of the heavy fractions of said residuum to produce undesirable amounts of coke and the like. The operation is so controlled that a relatively light residuum may be produced which constitutes in quantity about forty to eighty percent or more of the raw material charged. The liquid oil withdrawn in this operation from the pressure expansion chamber contains a large proportion 45 of lighter material suitable for cracking, which for instance, may be separated from the heavier portions of this non-vaporized oil by such a method as flashing under reduced pressure with or without additional heat, so that these lighter 50 portions vaporize and separate from the heavy residue, which latter is separately withdrawn.

The vapor separated by flashing under reduced pressure may be then condensed and this condensed liquid is generally returned to the cracking 55 system for retreatment, providing for the pro-

portion of reflux required for maintaining suitable conditions of operation.

However, in the practice of such operations, the withdrawal of from thirty to fifty percent more or less, of the raw material in the form of residuum from the flash chamber may not produce as high a percentage of gasoline-like products from the charging stock as could be obtained otherwise, because after the flashing operation, there still remains in the residuum withdrawn from the flash chamber a portion of lighter fractions which would, if separated, be suitable for cracking. I have further found in carrying out the process of conversion in the manner above described where the conditions of operation are so controlled that excess conversion of the non-vaporized oil in the pressure chamber is avoided, for instance, by maintaining a low level in said chamber and cooling the non-vaporized oil as soon as practicable possible, that the characteristics of this residuum which contains a relatively low proportion of coke-like or pitch-like materials, are such that if this solid or semi-solid material is allowed to separate from the lighter portions of the residuum, substantially all of the liquid residuum forms a charging stock very suitable for cracking.

It is the object of this invention, therefore, to maintain such conditions in the cracking zone that a relatively large percentage of light residuum is produced in the pressure expansion chamber; to stop undesirable reaction of this residuum as soon as possible, thereby preventing it from undergoing excess conversion which would result in excess coke and pitch and then flashing it preferably to such extent that gasoline-like fractions dissolved therein may be separated and collected; then permitting settling or separation of the relatively small percentage of solid or semi-solid matters from the liquid portion of the residuum, and then returning regulated quantities of said liquid portion of the non-vaporized oil to the cracking zone for further treatment commingled with fresh charging stock and reflux.

A controlled amount of the liquid portion of the non-vaporized oil may be withdrawn from the flash chamber together with the solid or semi-solid matter to facilitate removal of the latter from the process.

The invention is characterized by extreme flexibility. The process is adaptable to widely varying commercial conditions, being flexible enough to permit an operation in which a relatively low yield of gasoline-like fractions and a

relatively high yield of liquid residue suitable for use as fuel is produced, while being just as equally applicable to a situation in which it is desired to produce maximum yields of gasoline-like products and minimum yields of liquid residue.

Other objects, features and advantages of the present invention will be more apparent from the following description.

The single figure in the drawing is a diagrammatic elevational flow chart to illustrate the invention.

Referring more in detail to the drawing, the charging stock to be treated by the process may be charged through line 1 in which is interposed valve 1' and through line 1'' into a heating tube 2 mounted in furnace 3 which may be of any suitable design. From the tube 2 the heated oil is passed through transfer line 4 controlled by valve 5, being introduced into the expansion, reaction and/or separating drum 6. The drum 6 is of conventional type being provided with manholes 6' and with insulation if desired, to prevent loss through heat radiation. Vapors separating in the chamber 6 are removed from the upper portion thereof through vapor outlet line 7 controlled by valve 8, the line 7 discharging into the lower portion of a conventional dephlegmator 9, which may be provided with any suitable form of baffling element. In the dephlegmator 9 the vapors are subjected to dephlegmation to condense the insufficiently converted fractions. Vapors remaining uncondensed after passage through the dephlegmator 9, which comprise the sufficiently converted fractions, leave the top of the dephlegmator through vapor outlet line 10 controlled by valves 11, being condensed in condenser coil 12 and collected in receiver 14 which may be provided with the liquid drawoff line 15 controlled by valve 16, and with the incondensable gas relief line 17 controlled by valve 18.

Suitable cooling material may be introduced into the upper portion of the dephlegmator 9 through line 19 controlled by valves 20. If desired, charging stock may be introduced by means of pump 21 and line 22 provided with valves 23 into the upper portion of the dephlegmator 9 whereby it will be preheated, while at the same time assisting in fractionation of the vapors entering through line 7. The reflux condensate formed in the dephlegmator 9 together with the preheated unvaporized portions of the charging stock, is withdrawn from the bottom of the dephlegmator through line 24 controlled by valve 25 and directed to the charging line 1'' by means of hot oil pump 26. All or any regulated portion of the reflux condensate may be diverted from the line 1'' by suitable manipulation of valve 25' in line 24'. The conditions of temperature, super-atmospheric pressure and proportion of reflux condensate to charging oil are so maintained that a relatively large percentage of relatively light non-vaporized oil forms in drum 6. This non-vaporized oil is however, not permitted to accumulate in the drum, a low level or no level at all, being preferably maintained therein. This is effected by withdrawing the non-vaporized oil continuously from the bottom of the drum 6 through line 27 controlled by valve 28. The pressure is controlled by means of valve 28 and reduced through proper manipulation thereof to the proper degree. The reduction of pressure through the medium of valve 28 causes some cooling of the oil and helps thereby to arrest further reaction in this unvaporized oil.

The latter, under reduced pressure, is directed

to a flash-settling chamber 29 wherein the vapors produced by flashing of the non-vaporized oil separate from the heavier liquid portions. The degree of reduction of pressure through the manipulation of valve 28, and the temperature in the chamber 29 are preferably so controlled that only gasoline-like constituents contained in the non-vaporized oil withdrawn from chamber 6 are removed as vapors from the upper portion of chamber 29 through line 30 controlled by valve 31. These gasoline-like fractions may be condensed in condenser 32 and collected in receiver 34, which latter may be provided with suitable liquid drawoff line 35 controlled by valve 36 and with gas relief line 37 controlled by valve 38.

In this manner the intermediate fractions contained in the non-vaporized oil withdrawn from chamber 6 remain in a liquid state in the chamber 29 and help to thin the heavier portions thereof. The carbon, coke, sludge, and pitch or the like (which for convenience will be referred to as solid and semi-solid matter) contained in the non-vaporized oil withdrawn from chamber 6 settle out in the bottom of chamber 29, and it is one of the features of the present invention to assist the separation of these solid or semi-solid matters from the liquid portion by maintaining a substantial body of liquid oil in chamber 29, and also by keeping in a liquid state in said chamber substantially all fractions of oil heavier than gasoline. This separation of the solid and semi-solid matter from the relatively lighter liquid non-vaporized oil produces in the chamber 29 a relatively large proportion of substantially clean oil, which I have found to be most suitable for recracking. Therefore, as a feature of the present invention, I return this relatively clean oil produced by the separation of the gasoline-like fractions and solid and semi-solid matter from the non-vaporized oil produced in the process to the inlet of the heating tube 2 for retreatment. This oil may be withdrawn from the flash-settling chamber 29 through line 39 controlled by valve 40, the line 39 preferably connecting to the flash chamber 29 at a point substantially above its base so as to permit a space large enough for settling and accumulation of the solid and semi-solid matter. This oil is then taken by pump 41 and line 42 controlled by valve 43 and passed through charging line 1'' into the heating coil 2.

The temperature in the flash-settling chamber 29 may be controlled by any suitable means. For instance, I may employ a regulated portion of the relatively cool charging stock to be treated in the system to regulate this temperature in a heat interchange fashion. For this purpose, regulated quantities of the charging stock may be diverted from line 22 through line 44 controlled by valve 45 and introduced directly into contact with the contents of chamber 29 through spray 46. In this method of operation, the charging stock is directed to the heating coil 2 through the line 39 together with the relatively clean oil from chamber 29. Or the cooling of the contents of chamber 29 may be effected by keeping the charging stock out of contact with the material contained in said chamber. This may be effected by passing regulated quantities of the charging stock through line 47 controlled by valve 48 and through heat exchanging coil 49 positioned in the upper portion of chamber 29, from which coil the charging stock returns to line 22 through branch 50 controlled by valve 51. Any suitable quantity of the charging stock may

be directed to the chamber 29 and to the dephlegmator 9 by proper control of valves 23, 51, 48 and 45. Also any proportion of charging stock directed to the chamber 29 may be charged thereto directly or passed through said chamber in indirect contact by proper control of valves 51, 45 and 48.

Heavy material including solid and semi-solid matter separated in the chamber 29 may be withdrawn therefrom through line 52 controlled by valve 53 and directed to storage. Drum 6 may also be provided with the drain 54 controlled by valve 55.

It will be appreciated from the above description, that the process of the present invention is very flexible, and may be operated in many ways depending upon the characteristics of the oil treated, and the types of products desired.

For instance, it may be desirable to produce from a cracking stock a maximum of liquid products and a minimum of coke and gas, while at the same time producing a high yield of liquid residuum compatible with specifications as to its content of coke and solid matter. In operating in this manner, I may continuously withdraw from the bottom of the flash-settling chamber 29 a relatively large proportion of heavier residuum while returning to the cracking coil 2 through the lines illustrated, a small proportion of the liquid oil remaining in chamber 29 after separation of the solids and coke.

In another method of operation, it may be desirable to convert the charging stock into gasoline-like products and into coke and gas. I am aware that cracking processes have already been operated in such a manner as to produce substantially no liquid residue, but as far as I am aware, the production of coke from the process accumulated in the pressure reaction chamber. In some instances, this may be objectionable because the pressure reaction chamber is generally an expensive part of the apparatus, its size being limited not only by the cost of the drum, but by the pressure maintained thereon. The use of alternate chambers under pressure although possible, represents of course, a much greater investment.

By means of the present invention, I propose, in operating the process in this manner, to permit all of the carbon and solid matters produced in the process to accumulate in the chamber 29, which is maintained at a substantially lower pressure than the chamber 6, and generally at pressures slightly above atmospheric, or even at atmospheric pressure. It can be readily seen that this permits the use of alternate chambers with a lesser expense and easier operation, and that in this manner the length of the run may be prolonged far beyond the length of the runs made by other processes.

The high pressure cracking zone comprising tube 2, drum 6 and dephlegmator 9 may be maintained under suitable superatmospheric pressure say from 100 to 500 pounds more or less, while this pressure may be reduced in the chamber 39 through manipulation of valve 28 down to say atmospheric. The oil passing through the heating coil 2 may be heated to a temperature of say 850 to 900 degrees F. more or less, it being understood that this temperature is merely illustrative, and that a skilled operator will change conditions of temperature and pressure to suit the characteristics of the material treated, and the products desired.

As a further feature of the present invention,

I provide means for thinning the non-vaporized oil in chamber 6, or the non-vaporized residue in chamber 29 to help separation of the solid and semi-solid matter from the liquid portion. This may be effected for instance, by returning a portion or all of the reflux condensate from line 24 to the chamber 29 through branch line 56 controlled by valve 57. The raw oil may also be combined as hereinbefore described, with the reflux condensate by introduction to the dephlegmator. In this method of operation, all of the material for cracking will be withdrawn from the chamber 29 through line 39.

In another method of operation, it may be desirable to return regulated portions of the reflux condensate from the dephlegmator 9 to the drum 6 which may be effected by manipulation of the valve 59 in branch line 58.

I may also combine reflux in dephlegmator 9 with non-vaporized oil from drum 6 before it enters the flash chamber 29, by suitably controlling valve 60 in branch line 61 connecting lines 27 and 56.

All or any regulated portion of the condensed liquid collecting in receiver 34 may be returned through branch 62 controlled by valve 63 to the heating coil 2 for further treatment, if desired.

It is to be understood of course, that if it is found desirable to apply heat to either drum 6 and more particularly to the drum 29, that this is within the contemplation of the invention.

I claim as my invention:

1. The art of hydrocarbon oil conversion which comprises subjecting said oil to cracking conditions of temperature and superatmospheric pressure in a heating zone, passing the heated oil to a conversion zone, separating vaporous products from said heated oil, continuously withdrawing non-vaporized oil from said conversion zone at such a rate as to prevent substantial accumulation therein, reducing the pressure on said withdrawn oil while the latter is in heated condition whereby lighter fractions will be released therefrom in the form of vapors, maintaining said withdrawn oil in a substantial body, separating and removing the lighter vaporous fractions released therefrom, settling the solid and semi-solid portions of said body and removing from the upper portion of said body regulated portions of liquid oil freed from said solid and semi-solid matter, and returning same for re-treatment to the oil undergoing cracking.

2. The art of hydrocarbon oil conversion which comprises subjecting said oil to cracking conditions of temperature and superatmospheric pressure in a heating zone passing the heated oil to a conversion zone, permitting separating vaporous products from said heated oil, continuously withdrawing non-vaporized oil from said conversion zone at such a rate as to prevent substantial accumulation therein, reducing the pressure on said withdrawn oil while the latter is in heated condition whereby lighter fractions will be released therefrom in the form of vapors, maintaining said withdrawn oil in a substantial body, separating and removing the lighter vaporous fractions released therefrom, settling the solid and semi-solid portions of said body and removing from the upper portion of said body regulated portions of liquid oil freed from said solid and semi-solid matter, and returning same under the influence of applied pump pressure for re-treatment to the oil undergoing cracking.

3. A hydrocarbon oil cracking process which comprises passing the oil in a restricted stream

through a heating zone and heating the same therein to cracking temperature under pressure, discharging the heated oil into an enlarged vapor separating zone maintained under reaction conditions and separating evolved vapors from unvaporized oil therein, removing the vapors from said separating zone, separately withdrawing the unvaporized oil from said separating zone at such a rate as to prevent substantial accumulation of unvaporized oil therein, lowering the pres-

sure on the withdrawn unvaporized oil while in heated condition whereby lighter fractions thereof are released, separating solid and semi-solid matter from the remaining liquid unvaporized oil, and returning regulated portions of the remaining liquid unvaporized oil from which solid and semi-solid matter has been removed to said heating zone.
